Application May 26, 1934, Serial No. 727,746

20 Claims. (Cl. 200—48)

My invention relates to circuit interrupters, and particularly to outdoor disconnecting switches for use with medium and high voltage transmission circuits.

5 Switches of this type ordinarily comprise a pair of spaced insulators, a contact means mounted on each of the insulators, a blade for bridging the contact means, and a means for actuating the blade. It is desirable that the plane of movement 10 of the blade be parallel to the axes of the insulators, this construction yielding a vertical break switch which occupies a minimum of ground space. It is also desirable that the insulator columns be subjected to as little cantilever stress as 15 is possible, since all of the economically practicable insulators, while capable of resisting relatively large torsional stresses, fail when subjected to relatively low cantilever stresses.

These switches are generally used for disconnecting or sectionalizing portions of a transmission line. Usually they are mounted outdoors and are subjected to very severe weather conditions as a result of ice or sleet formations.

Moreover, in the normal course of events, the 25 switches are operated very infrequently, thus providing an almost ideal condition for oxide and corrosion formation. The switches must be low in cost due to the large number used; they must be capable of reliable operation under the most 30 adverse conditions without unduly straining the supporting insulators; the contact must include means for cutting through corrosion during the circuit closing operation so as to assure good electrical contact; and the switches must be inherently safe so as to prevent injury to the operator or to the protected equipment.

These requirements are somewhat conflicting, because it is ordinarily very difficult to secure high contact pressure, with a wiping or corrosion cutting engagement of the contacts during 40 the circuit closing operation, without subjecting either one or both of the insulators to a cantilever stress which is substantially proportional to the contact pressure secured. One method of accom- 45 plishing the desired contact pressure and wiping action between the engaging contact surfaces without unduly straining the supporting insulators consists in the rotation of the entire switch blade. This arrangement is objectionable in that 50 it has a tendency to freeze up during the winter time and has not proven entirely satisfactory.

Another arrangement used in the past consists in the provision of two longitudinally movable blades, both of which are supported upon one of 55 the insulator columns. A switch of this type is

disclosed and described in my copending applications, Serial Nos. 697,611 now Patent No. 2,027,900, issued Jan. 14, 1936 and 697,612, both of which are assigned to the assignee of this invention, and it is with improving switches of this 5 general type that the present invention is particularly concerned.

The principal object of the present invention is to provide an improved high voltage disconnecting switch that shall be inexpensive to manufacture, that shall be safe and reliable in operation, and that shall include means for securing high pressure contact accompanied by a wiping engagement of the cooperating contact surfaces during the circuit closing operation, without unduly straining the supporting insulator columns. 10

This object of my invention is accomplished through the provision of a switch utilizing a parallel blade construction. One of the blades is adapted to move longitudinally of the other during the circuit closing operation so as to effect a wiping engagement accompanied by high contact pressure between the cooperating contact surfaces of the blade and the contact. The other blade includes means operable during the circuit closing operation to mechanically engage the outboard insulator column so as to rigidly interconnect both of the insulators, thereby limiting the stress which might be placed on either column during the operation of the switch, and at 20 the same time providing a structure of considerable strength and rigidity. The interconnecting means in the preferred embodiment of my invention automatically adapts itself to a considerable amount of relative movement of the insulator 25 columns, and thereby assures satisfactory operation of the switch despite any relative movement 30 which might be produced as a result of adverse weather conditions or damage to the switch 35 itself.

A further object of my invention is to provide an improved form of multiple blade construction partly adaptable for use with disconnecting switches for high voltage circuits, the blade to have sufficient inherent rigidity to prevent undue 40 movement of the contact portion thereof which might result from wind acting upon the long span ordinarily encountered in high voltage switches.

A still further object of my invention is to provide an improved disconnecting switch which 45 shall accomplish the above stated objects and operate satisfactorily despite the formation of ice and sleet or the like.

These and other objects of my invention will 50 be more clearly understood from the following 55

description of an embodiment of my invention as applied to a three-insulator vertical-break disconnecting switch.

Referring to the drawings:

5 Figure 1 is an elevational view showing a three-insulator vertical-break disconnecting switch embodying the principal features of my invention. The switch is in the closed-circuit position.

10 Fig. 2 is a fragmentary elevational view showing the disconnecting switch illustrated in Fig. 1 in the partially opened position.

15 Fig. 3 is a plan view of the disconnecting switch shown in Figs. 1 and 2 in the closed-circuit position.

20 Fig. 4 is a fragmentary elevational view showing the disconnecting switch shown in Figs. 1 to 3 in the open-circuit position.

25 Fig. 5 is a fragmentary plan view of the contact structure of the switch illustrated in Figs. 1 to 4 in the partially opened position.

30 Fig. 6 is a sectional view on the line VI—VI of Fig. 1.

35 Fig. 7 is a sectional view on the line VII—VII of Fig. 6.

40 Fig. 8 is a perspective view of the support element for the lower blade, and

45 Fig. 9 is a perspective view of the support link for the upper blade.

50 As shown in the drawings, the preferred embodiment of my invention includes a base or support member 1 for the switch, a pair of stationary insulator columns 3 and 5 which are rigidly mounted upon the support member 1 through the agency of bolts 7, a contact jaw 9 mounted upon the upper insulator 3, a pair of blade members 11 and 13 mechanically connected to each other by a pair of link members 15 at the upper end and a single link member 17 at the lower end, a rotatable insulator 19 likewise mounted upon the base 1, and actuating means intermediate the rotatable insulator 19 and the blade means.

55 The two stationary insulator columns 3 and 5 and the rotatable insulator column 19 are of the usual high voltage type and comprise a number of ceramic rain shields cemented together with a cap 23 of conducting material at the upper end and a supporting member 25 at the lower end. Each of the supporting members 25 terminates in a flange 27, which in the case of the two stationary insulators 3 and 5 is directly bolted to the base 1, a suitable spacing washer 29 being provided for securing the desired positioning of the insulator columns. The flange 27 of the insulator column 19 is directly bolted to a bearing 31 which permits the insulator column 19 to be rotated to effect the actuation of the switch.

60 The U-shaped contact jaw 19, which is shown particularly in Figs. 6 and 7 is bolted to the insulator cap 23 of the upper stationary insulator 3 by means of suitable bolts 33, and comprises a pair of upstanding side portions 35 which are cast integral therewith. Each of the side portions 35 is provided with a contact portion 37 and a guide portion 39. The guide portions 39 are disposed at an angle with respect to the contact portions 37 in order to facilitate the entry of the cooperating portions of the blade during the circuit closing operation. The contact portion 37 of the right-hand upstanding member 35 is machined in the form of a tooth in order to permit the stationary insulators 3 and 5 to be rigidly interconnected during the circuit closing operation, and the contact portion 37 of the other 75 side of the jaw is rounded in order to permit the

cooperating contact portion of the blade to engage that portion with a wiping action during the operation of the switch.

70 A U-shaped support member 41, which is shown particularly in Figs. 1 and 3, is rigidly affixed to the insulator cap of the secondary stationary insulator by means of suitable bolts 43. This U-shaped support member, as will be described in some detail later, is utilized for providing a pivot point for permitting the blade to be swung to the open and to the closed-circuit position during the operation of the switch.

75 A flat plate member 45, also shown in Figs. 1 and 3, is positioned beneath the U-shaped support member 41. This plate member 45 is provided with a suitable opening 47, slightly greater in diameter than the base portion 51 of the actuating crank 49, which is bolted to the cap portion 23 of the rotatable insulator 19 by the bolts 53. The opening 47 engages the base portion 51 of the crank arm 49 in a manner similar to a journal and shaft and serves, during the operation to the switch, as a tie for preventing undue relative movement between the rotatable insulator 19 and the mechanically interconnected stationary insulators.

80 The lower portion of the plate member 45 is provided with an opening (not shown) for engaging the bolt 55 which serves to electrically connect the lower terminal 57 of the switch thereto. The upper terminal 59 of the switch is supported upon a suitable outwardly projecting portion 61 cast integral with the U-shaped stationary contact 9.

85 The rotatable insulator column 19 is supported upon the base 1 through the rotatable bearing 31 and is provided at the lower portion thereof with a crank member 65 which is adapted to be engaged by the switch operating lever (not shown). The outer portion of the actuating crank 49 which is supported upon the rotatable insulator 19 is provided with a bifurcated portion 67 having suitably disposed openings therein for engaging the pin 69 intermediate the actuating crank and the tie member 71.

90 The blade comprises, as mentioned above, a pair of tubular members 11 and 13 which are joined together by suitable links so as to form a quadrilateral assemblage which is pivotally supported at one of the corners thereof. The longitudinal axes of the two blade members are skewed at all times in order that the blade assemblage shall possess a maximum of rigidity. This skewing of the blades is shown particularly in Figs. 1, 2 and 3 and is of particular value in securing a satisfactory high voltage switch because the long spans (sometimes as much as eighteen feet) which must be bridged by the blade in switches of this type make it imperative that the blade shall be very rigid.

95 The lower blade member 11 comprises a solid copper rod of considerable inherent rigidity, which is provided with a contact member 73 at its outer end and a bifurcated support member 75 (Fig. 8) at its inner end. The member 75, as is shown in Figs. 1 to 3, is adapted to be pivotally supported upon the U-shaped support member 41 affixed to the lower stationary insulator column 5 through the agency of a pivot pin 77. This pivot pin 77 also serves as a support for the operating link 17 which is disposed intermediate the two blade members 11 and 13 at their pivoted end.

100 As is shown particularly in Fig. 8, both of the

opposed sides 79 of the bifurcated support member 75 are provided with an outwardly extending projection 81 cast integrally therewith. These projections 81 are adapted to cooperate with 5 suitable projections 83 forming a part of the upperstanding sides of the U-shaped support member 41 in order to limit the upward movement of the blade during the circuit opening operation.

The upper blade member 13 comprises a similar body portion of copper rod, a contact member 85, and a bifurcated support member 87 which is shown particularly in Figs. 1 and 3. The outer portion of the operating link 17 (Fig. 9) is provided with a pair of opposed openings 89, adapted 10 to engage the pivot pin 91 which serves to pivotally interconnect the upper blade member 13 and the operating link 17.

The contact member 73 for the lower blade 11 comprises a cast member having a suitable body 20 portion for engaging the outer end of the blade proper, and a contact portion 93 having a plurality of teeth formed therein. These teeth are of substantially the same outline as the toothed contact portion 37 of the right hand side of the 25 contact jaw 9 and serve during the circuit closing operation, as a means for interconnecting the two stationary insulator columns. A plurality of teeth are provided in order that the blade shall be capable of automatically accommodating itself 30 to a considerable amount of relative movement of the stationary insulators which might result during high winds or other unusual conditions.

The contact member 85 for the upper blade member 13 is essentially similar to the contact member 73 for the lower blade, except that the contact portion 95 thereof is machined flat. During the operation of the switch the upper blade 13 moves longitudinally with respect to the lower blade and the cooperating contact surfaces 40 of the contact portion 85 of the upper blade and the left-hand portion 35 of the jaw engage with a wiping action. The contact surface of the left-hand portion 37 of the jaw 9, as explained above, is rounded in order to restrict the contact 45 surfaces to a small area.

The tie member 71 is provided for mechanically interconnecting the actuating crank 49 affixed to the rotatable insulator 19 and the blade assemblage, a pair of universal joint means 97 and 99 50 being provided to permit the switch actuating mechanism to accommodate itself to the rather complex movement of the various parts of the blade means. The outer ends of the two blade members are mechanically interconnected by the tie links 15 and two pivot pins 101 as is shown particularly in Figs. 6 and 7. These links 15, in combination with the main actuating link 17, serve to define the movement of the two blade members 11 and 13, and during the closing operation of the switch cause the contact portions 93 and 95 to move away from each other in order to effect a high pressure engagement between the cooperating contact surfaces and to mechanically connect the stationary insulator columns.

65 A flat leaf spring 103 is provided for biasing the quadrilateral blade assemblage to the position shown in Figs. 2 and 4. This biasing is necessary in order that the contact portions 93 and 95 of the two blade members may be readily moved into the contact jaw during the operation of the device. As pointed out above, the contact portions 93 and 95 of the blade members move away from each other during the closing operation of the switch, and since the separation of the contact surfaces 70 75 37 formed in the opposed sides 35 of the jaw

member is greater than the separation of the space through which the contact portions of the blades must pass when moving through the jaw during the operation of the switch, it is necessary that the contact portions of the blade members be biased toward each other, i. e. to a position where the blade can be readily moved into and out of the contact jaw. The flat leaf spring 103 is particularly desirable for accomplishing this purpose in that it is not readily clogged by ice, 10 and if ice should be formed about it, it will subject the ice to a tensional stress during the operation of the switch, and thereby cause it to break without undue strain being placed upon the operating mechanism. The actuating link 17 is provided with a suitable machined portion 105 having a threaded hole 107 therein for permitting one end of the spring 103 to be mechanically connected thereto, and the bifurcated support 75 for the lower blade member is provided with a similar machined portion for engaging the other end of the spring, bolts 109 being utilized to fasten the ends of the spring to the two members. Flexible shunts 111 and 113 are provided for electrically interconnecting the two blade members 11 20 and 13 and for connecting those members to the cap portion 23 of the lower stationary insulator 5, the bolts 115 serving to effect the desired electrical connections.

The electrical circuits through the switch is 30 very direct. Beginning with the upper terminal 59, the current flows through the stationary contact jaw 9, the cooperating contact portions 93 and 95 of the two blade members 11 and 13, thence through the body portions of the blade 35 members the shunts 111, to the cap portion 23 of the second stationary insulator 5, and thence through the plate member 45 which is electrically connected to the cap portion of the second stationary insulator to the other terminal 57. 40

The switch is shown in the closed-circuit position in Figs. 1 and 3, and it will be noted that the center of the pin 69 which connects the operated crank 49 with the tie link 71 has been moved to a position somewhat to the left of the line connecting the center of the rotatable insulator 19 and the pin 117 which serves to connect the link 71 with the blade assemblage. Further rotation of the rotatable insulator in the counter-clockwise direction is prevented by suitable stop means 45 (not shown). The mechanism is thus effectively latched against movement toward the open-circuit position by virtue of the fact that all of the stress which may be placed upon the tie link 71 tending to open the switch is taken up by the stop 50 means. The other end of the switch is likewise latched in the closed-circuit position by virtue of the fact that the contacting portions 93 and 95 of the two blade members 11 and 13 have moved away from each other a distance greater than the 55 separation of the restricted mid-portion 119 (Fig. 6) of the stationary contact jaw 9.

To open the switch the insulator 19 is rotated in a clockwise direction from the position shown in Figs. 1 and 3. The first effect of this rotation is to move the pivot pin 69 from the over-center position to a position where the rotation of the insulator and the actuating crank 49 moves the link 71 away from the fully-closed position to the position shown in Fig. 2. The blade 70 assemblage has not, during this movement, rotated about the main support pin 11, but the entire effect of the movement of the link 71 has been to move the upper blade 13 longitudinally, in an axial direction, of the lower blade 11. The 75

limits of this longitudinal movement are defined by the link members 15 and 17 which mechanically interconnect the two blade members, and the immediate effect is to cause the contact portions 93 and 95 of the blade members to move toward each other a sufficient distance to permit the blade means to disengage the contact jaw. Further movement of the rotatable insulator will cause the quadrilateral blade assemblage to rotate about the pivot pin 11 to the open-circuit position shown in Fig. 4.

The flat leaf spring 103 serves to maintain the blade members against movement toward the expanded or closed-circuit position when the switch is open. The upward swingable movement of the interconnected blade members is defined, as mentioned above, by the engagement of the projections 81 upon the lower support member 75 with the projections 83 forming a part of the U-shaped support member 41 affixed to the cap of the lower stationary insulator.

To close the switch the insulator 19 is rotated in a counter-clockwise direction from the position shown in Fig. 4. This rotation causes the blade to swing back into engagement with the jaw, the flat spring 103 maintaining the proper positioning of the blades, and upon further rotation of the insulator the upper blade member 13 is caused to move longitudinally in an axial direction of the lower blade member 11 to effect engagement of the cooperating contact surfaces. The toothed portion 93 of the lower blade member 11 engages the similarly proportioned contact surfaces 37 of the right hand side 35 of the jaw 9, and as the circuit closing operation is completed, serves to effect a rigid interconnecting of the two stationary insulator columns 3 and 5. The contact portion 95 of the upper blade member 13 engages the rounded contact portion 37 of the left hand side 35 of the jaw member with a wiping action which effectively cuts through any corrosion or oxide which may exist between the cooperating contact surfaces.

Since the two stationary insulators 3 and 5 are mechanically interconnected during the circuit-closing operation, by virtue of the engagement of the toothed portion 93 of the lower blade member 11 with the jaw 9, the cantilever stress which results from the longitudinal movement 50 of the blade 13 is divided substantially equally between the two insulator columns. The cantilever stress is also taken up to a more or less extent through the shaft and journal engagement of the rotatable insulator 19 and the member 45. The combined result of the mechanical interconnecting of this insulator column is to prevent 55 excessive cantilever stresses on either of the stationary insulator columns or the rotatable insulator column during the operation of the switch. In effect all of the insulator columns are mechanically interconnected, and each aids the others in producing a rigid structure which will operate satisfactorily when subjected to the most adverse operating conditions.

An arcing horn 121 is affixed to the base portion of the stationary contact jaw 9 and is adapted to cooperate with a suitably dimensioned arcing horn 123 affixed to the contact portion 93 of the lower blade member 11. This arrangement causes the electrical circuit through the switch to be finally interrupted not at the engaging contact portions of the blade and jaw members but at the arcing horns, and permits the switch to be used for interrupting low amper-

age circuits without damage to the engaging contact surfaces.

The skewed relation of the blade members is maintained at all times during the operation of the switch in order to impart rigidity to the blade assemblage. The link members 15 which interconnect the two blade members 11 and 13 at their outer portion are positioned some distance away from the engaging contact surfaces. This is done in order that the resilience of the blade members themselves may be used for securing the desired contact pressure between the engaging contact surfaces during the operation of the switch.

It will thus be seen that I have disclosed an improved high pressure contact disconnecting switch which includes a pair of spaced stationary insulator columns, a blade for bridging the conducting means affixed to the top portion of each of the two insulator columns, and a rotatable insulator having means associated therewith for actuating the blade. The cooperating contact portions of the blade and the stationary contact are provided with engaging toothed portions which, during the operation of the switch, serve to mechanically interconnect both of the two stationary insulator columns in order to prevent either one of these columns from being subjected to undue cantilever stresses. Moreover, the cooperating interconnecting means are automatically adjustable in order to compensate for any relative movement of the insulator columns which might develop during the operation of the switch.

Further, my improved switch includes an operating mechanism which is so arranged that the movable portions exposed to ice formation move, during the operation of the switch, so as to cause such ice as may be formed to be stressed either in tension or in shear, thus practically eliminating any possibility of the switch freezing fast in either the opened or the closed circuit position. When my improved switch is in the closed-circuit position the blade and the operating mechanism are both securely latched against movement as a result of magnetic stresses, and at the same time the latching means are both entirely releasable through the rotation of the single rotatable insulator.

Attention is directed to the fact that the various parts of the switch shown in this embodiment of my invention are all mounted on single insulators. It is well known in the art that the insulator columns for disconnecting switches may comprise any number of the single insulators and it is my intention that the word "insulator" or "insulator column" shall include either a single insulator or a plurality of insulators.

While in accordance with the patent statutes I have disclosed the details of a preferred embodiment of my invention, it is to be understood that many of these details are merely illustrative and that variations in their precise form will not be only possible but necessary in some applications. I desire, therefore, that my invention should be limited only as set forth in the appended claims and by the prior art.

I claim as my invention:

1. In an electrical switch, a pair of spaced insulator columns, conducting means mounted on each of said columns, movable blade means for bridging said conducting means to provide an electrical circuit therebetween, and actuating means for moving said blade means to the open and to the closed-circuit position, said blade

- means and said conducting means including co-operating means engageable at any one of a plurality of points to rigidly interconnect said insulator columns so as to prevent relative movement therebetween during at least a portion of the circuit-closing operation, and said actuating means moving the switch into final closed-circuit position after said insulator columns are rigidly interconnected.
10. 2. In an electrical switch, a pair of spaced insulator columns, conducting means mounted on each of said columns, movable blade means for bridging said conducting means to provide an electrical circuit therebetween, and actuating means for moving said blade means to the open and to the closed-circuit position, said blade means and said conducting means including co-operating means operable to rigidly interconnect said insulator columns so as to prevent relative movement therebetween during at least a portion of the circuit-closing operation, said interconnecting means comprising toothed members which engage to effect the mechanical interconnecting of said insulator columns and which automatically accommodate themselves to a considerable amount of relative movement of said insulating columns without subjecting said columns to substantial stress during the operation of said switch.
20. 3. In an electrical switch, a pair of spaced insulator columns, conducting means mounted on each of said columns, movable blade members for bridging said conducting means to open and to close the electrical circuit therebetween, means for supporting said blade means for swingable movement, and actuating means for moving said blade means to the open and to the closed-circuit position, said blade means and said conducting means being provided with cooperating means operable to cause said insulator columns to be rigidly interconnected so as to prevent relative movement therebetween during at least the final portion of the circuit-closing operation, said co-operating means including members which are readily movable into and out of engagement with each other to effect said rigid interconnection at any one of a plurality of points at which said cooperating means engage when said blade means is swung from one position to the other but which prevent relative movement of said insulating columns after the engagement of said cooperating means, and said actuating means moving the switch into final closed-circuit position after said insulator columns are rigidly interconnected.
45. 4. In an electrical switch, a pair of spaced insulator columns, conducting means mounted on each of said columns, movable blade means for bridging said conducting means to open and to close the electrical circuit therebetween, means for supporting said blade means for swingable movement, and actuating means for moving said blade means to the open and to the closed-circuit position, said blade means and said conducting means being provided with cooperating means operable to cause said insulator columns to be rigidly interconnected so as to prevent relative movement therebetween during at least a portion of the circuit closing operation, said cooperating means including toothed members at least one of which is provided with a plurality of teeth, which are readily movable into and out of engagement with each other when said blade means is swung from one position to the other but which prevent relative movement of said insulating columns when in the engaged position, the multiple tooth

feature of said engaging members causing said interconnecting means to automatically accommodate itself to a considerable amount of relative movement of said insulating columns without subjecting said columns to substantial cantilever stress during the interconnecting operation. 5

5. In an electrical switch, a pair of spaced, insulator columns, a contact means supported upon one of said columns, a blade means, means for supporting said blade means upon the other 10 of said columns for swingable movement into and out of engagement with said contact means to close and to open the electrical circuit through said switch, and actuating means for moving said blade means, said blade means including means 15 adapted to cooperate with means forming a part of said contact means when said blade means is being moved to the closed-circuit position to rigidly interconnect said insulator columns with any one of a plurality of different distances between the ends thereof, and said actuating means forcing said contact means and blade means into final engagement after said insulator columns are rigidly interconnected. 20

6. In an electrical switch, a pair of spaced, 25 stationary insulator columns, a contact means supported upon one of said columns, a blade means, means for supporting said blade means upon the other of said columns for swingable movement into and out of engagement with said 30 contact means to close and to open the electrical circuit through said switch, and actuating means for said blade means, said blade means and said contact means having cooperating toothed portions which engage when said blade means is 35 swung into the closed circuit position to rigidly interconnect said insulator columns so as to prevent substantial relative movement therebetween, the toothed feature of said cooperating portions causing said interconnecting means to automatically accommodate itself to considerable relative movement of said insulating columns without subjecting said columns to substantial stress during the operation of said switch. 40

7. In an electrical switch, a pair of spaced insulator columns, conducting means supported on each of said columns, movable blade means for bridging said conducting means to provide an electrical circuit therebetween, said blade means and said conducting means having cooperating 50 contact portions, and actuating means for moving said blade means to the open and to the closed-circuit position, said blade means comprising a pair of blade members at least one of which is movable longitudinally with respect to the other 55 during the circuit-closing operation to cause the final intimate engagement between the cooperating contact portions of said blade means and said conducting means, said blade means and said conducting means being provided with cooperating 60 means which mechanically interconnect said insulator columns at any one of a plurality of points at which said cooperating means happen to engage during the circuit-closing operation in order to prevent relative displacement of 65 the said columns when said blade member is moved longitudinally with respect to the said other blade member.

8. In an electrical switch, a pair of spaced, insulator columns, conducting means supported on 70 each of said columns, movable blade means for bridging said conducting means to provide an electrical circuit therebetween, said blade means and said conducting means having cooperating contact portions, and actuating means for mov- 75

ing said blade means to the open and to the closed-circuit position, said blade means comprising a pair of blade members at least one of which is movable longitudinally with respect to the other during the circuit closing operation to cause an intimate engagement between the co-operating contact portions of said blade means and said conducting means, said blade means and said conducting means being provided with toothed members which serve to mechanically interconnect said insulator columns during at least a portion of the circuit closing operation in order to prevent relative displacement of the said columns when said blade member is moved longitudinally with respect to the said other blade member, the toothed feature of said cooperating portions causing said interconnecting means to automatically accommodate itself to considerable relative movement of said insulating columns without subjecting said columns to substantial stress during the operation of said switch.

9. In an electrical switch, a pair of spaced, insulator columns, a contact means supported upon one of said columns, a blade means, means for supporting said blade means upon the other of said columns for swingable movement into and out of engagement with said contact means to close and to open the electrical circuit through said switch, and actuating means for said blade means, said blade means comprising a pair of blade members at least one of which is movable longitudinally with respect to the other during the final part of the circuit closing operation to cause high pressure engagement between the co-operating contact portions of said blade means and said contact means, said blade means and said contact means being provided with cooperating means which mechanically interconnect said insulator columns prior to said final circuit closing operation in order to prevent relative displacement of the said columns when said blade member is moved longitudinally with respect to the said other blade member, and said cooperating means being engageable to interconnect said insulator columns with any one of a plurality of different distances between the ends thereof carrying said contact means and said blade means.

10. In an electrical switch, a pair of spaced, stationary insulator columns, a contact means supported upon one of said columns, a blade means, means for supporting said blade means upon the other of said columns for swingable movement into and out of engagement with said contact means to close and to open the electrical circuit through said switch, and actuating means for said blade means, said blade means comprising a pair of blade members at least one of which is movable longitudinally with respect to the other during the circuit-closing operation to cause an intimate engagement between the co-operating contact portions of said blade means and said contact means, said cooperating contact portions including engaging toothed members, at least one of which is provided with a plurality of teeth, which serve to mechanically interconnect said insulator columns during at least a portion of the circuit-closing operation in order to prevent relative movement of said insulating columns during the operation of said switch, the multiple tooth feature of said engaging contact portion causing said interconnecting means to automatically accommodate itself to a considerable amount of relative movement of said insulating columns without subjecting said columns to sub-

stantial stress during the operation of said switch.

11. In an electric switch, a pair of spaced insulator columns, contact means supported upon one of said columns, a blade means pivotally supported on the other of said columns, for swingable movement into and out of engagement with said contact means, and actuating means for said blade means, the engaging contact portions of said blade means and said contact means including cooperating toothed members which serve to rigidly interconnect said insulating columns when said switch is in the closed-circuit position, and which are so arranged that they automatically accommodate themselves to a considerable amount of relative movement of said insulator columns without subjecting those columns to substantial cantilever stress during the interconnecting operation.

12. In an electric switch, a pair of spaced stationary insulator columns, a contact means supported upon one of said columns, a blade means, and actuating means for moving said blade means to open and to close said switch, said blade means comprising a pair of blade members each of which has a contact portion for engaging co-operating contact portions forming a part of said contact means, said blade members being joined together by a pair of link members so as to form a quadrilateral assemblage, said assemblage being pivotally supported at one of its corners to permit both of said blade members to be swung into and out of engagement with said contact means and to permit one of said blade members to be moved longitudinally of the other, and a flat leaf spring, mechanically connected at one of its ends to one of said blade members and at the other of its ends to one of said link members, for biasing said assemblage to a predetermined position, said spring being looped about one of the corners of said quadrilateral assemblage.

13. In an electric switch, a contact means, a movable blade structure, support means for said blade structure, and actuating means for moving said blade structure into and out of engagement with said contact means to operate said switch, said blade structure comprising a pair of blade members which are mechanically interconnected at both ends thereof, and the longitudinal axes of said blade members being skewed with respect to each other in all positions of the switch in order to increase the inherent rigidity of said blade structure.

14. In an electric switch, a contact means, a movable blade structure, support means for said blade structure, and actuating means for moving said blade structure into and out of engagement with said contact means to operate said switch, said blade structure and said contact means having cooperating contact portions, said blade structure comprising a pair of mechanically interconnected blade members, which are movable as a unit into and out of engagement with said contact means, and at least one of which is movable longitudinally with respect to the other during the circuit-closing operation to cause an intimate engagement between the co-operating contact portions of said blade structure and said contact means, one of said blade members having a fixed pivot and the longitudinal axes of said blade members being skewed with respect to each other in order to increase the inherent rigidity of said blade structure.

15. In an electric switch, a contact means, a movable blade structure, support means for said

- blade structure, and actuating means for moving said blade structure into and out of engagement with said contact means to operate said switch, said blade structure and said contact means having cooperating contact portions, said blade structure comprising a pair of blade members which are mechanically connected to each other by a pair of spaced link members, each of which is pivotally affixed at either of its ends to one of 5 said blades so as to form a quadrilateral assemblage, which assemblage is movable as a unit into and out of engagement with said contact means, and at least one of said blade members being movable longitudinally with respect to the 10 other during the circuit closing operation to cause an intimate engagement between the cooperating contact portions of said blade structure and said contact means, the longitudinal axes of said blade members being skewed with 15 respect to each other in all positions of the switch in order to increase the inherent rigidity of said blade structure.
16. In an electric switch, a pair of spaced insulator columns, a contact means supported upon 20 one of said columns, a blade means supported on the other of said columns for swingable movement into and out of engagement with said contact means, actuating means for moving said blade means, said blade means comprising a 25 pair of blade members which are mechanically connected to each other at least when said switch is in the closed circuit position to form a generally quadrilateral assemblage, each of said blade members having a contact portion adapted 30 to engage said contact means, one of said blade members being movable only about the axis of support of said blade means and the other of said blade members being movable longitudinally with respect to said first mentioned blade member, during each closing operation of said switch, and means actuatable in response to said longitudinal movement to effect an intimate engagement 35 between the cooperating contact portions of said blade member and said contact means, the contact portions of said first mentioned blade member and said contact means including cooperating toothed members which serve to mechanically interconnect said insulator columns during at least a portion of the circuit closing operation of said 40 switch, in order to prevent relative movement of said insulating columns when said last mentioned blade member is moved longitudinally with respect to said first mentioned blade member.
17. In an electric switch, a pair of spaced insulator columns, a contact means supported upon one of said columns, a blade means supported upon the other of said columns for swingable movement into and out of engagement with said contact jaw, actuating means for said blade means, said blade means comprising a pair of blade members which are mechanically connected to each other by suitable spaced linkages so as to form a quadrilateral assemblage, one of said blade members being supported for movement only about the axis of support of said blade means and the other of said blade members being movable longitudinally with respect to the first mentioned blade member during each closing operation of said switch to actuate said linkages 50 and thereby effect an intimate engagement between the cooperating contact portions of said 55
- blade members and said contact means, the engaging contact portions of said first mentioned blade member and said contact means comprising cooperating toothed members which serve to mechanically interconnect said insulator columns during at least a portion of the circuit closing operation in order to prevent relative movement of said insulating columns when said last mentioned blade member is moved longitudinally with respect to said first mentioned blade 60 member of said switch, the toothed feature of said engaging contact portions being so arranged that said interconnecting means automatically accommodates itself to a considerable amount of relative movement of said insulating columns 65 without subjecting those columns to substantial cantilever stress during the operation of said switch.
18. In an electric switch, a contact, and a blade means supported for swingable movement about a fixed pivot into and out of engagement therewith, the engaging portions of said contact and said blade means including cooperating toothed members which engage when said switch is in the closed circuit position, and at least one of said cooperating members being provided with a plurality of teeth in order that said members shall engage in any one of a plurality of positions.
19. In an electric switch, a pair of spaced insulator columns, a contact supported upon one column, and a blade means supported upon the other column for swingable movement about a fixed pivot into and out of engagement with said contact, the engaging portions of said contact and said blade means including cooperating toothed members which engage when said switch is in the closed circuit position to rigidly interconnect said columns, and at least one of said cooperating members being provided with a plurality of teeth in order that said members shall engage in any one of a plurality of positions.
20. In an electric switch, a pair of spaced insulator columns, a contact supported upon one of said columns, a blade means supported on the other of said columns for swingable movement about a fixed pivot into and out of engagement with said contact means, actuating means for said blade means, said blade means comprising a pair of blade members each of which has a contact portion adapted to engage said contact means, one of said blade members being movable only about the fixed axis of support of said blade means and the other of said blade members being movable longitudinally with respect to said first mentioned blade member during each closing operation of said switch, and means actuatable in response to said longitudinal movement to effect an intimate engagement between the cooperating contact portions of said blade members and said contact means, the engaging contact portions of said first mentioned blade member and said contact means including cooperating toothed members which engage when said switch is in the closed circuit position to rigidly interconnect said insulator columns, and at least one of said cooperating members being provided with a plurality of teeth in order that said members shall engage and interconnect said columns in any one of a plurality of positions.
